SANDER

Wayne A. Baldwin, Watertown, N. Y., assignor to
The New York Air Brake Company, a corpora-
tion of New Jersey

Application May 15, 1944, Serial No. 535,681

2 Claims. (Cl. 291—11)

1

This invention relates to sanders, particularly sanders for use on locomotives.

Where sanders are mounted on the side of the boiler of a steam locomotive below the sand box it is sometimes necessary to provide distinct forms of sanders (i. e. rights and lefts) for the two sides of the locomotive.

One feature of the invention is the arrangement of the sander so that it can be assembled in two different ways and thus produce either a righthand sander or a lefthand sander.

Another feature of the invention is the use of a self-sustaining Venturi ejector assembly which may be mounted in the sander body in two different positions to effect the reversal above mentioned. The ejector assembly includes a sustaining tube having positive positioning means and a lateral port which communicates with the sand chamber of the trap body. At the outlet end of this tube there is a removably mounted Venturi throat which is desirably formed of rubber and which may be variously dimensioned to suit particular conditions. This interchangeable throat has a projecting end which performs a secondary function in that it serves as a sealing gasket. Also removably mounted in the tube is a nozzle assembly. This nozzle assembly has a removable tip which coordinates certain related factors, the size of the nozzle port, the character of an entrance strainer which protects the nozzle port, and a rim which encircles the nozzle port and controls the width of the entrance aperture through which sand reaches the Venturi throat. Thus it is possible to manufacture the nozzle tip in various sizes in which the dimension of all functionally related parts are coordinated.

The preferred embodiment of the invention is illustrated in the accompanying drawing, in which

Figure 1 is an elevation of the trap as it would appear on the righthand side of the locomotive boiler with the air supply connection toward the cab, that is toward the rear end of the locomotive, the sand discharging connection leading forward from the trap.

Figure 2 is a vertical section on the medial plane of the trap.

Figure 3 is a section on the line 3—3 of Figure 2.

The body of the trap is made up of two parts, the body proper 6 which is open at the front, and the cap 7 which is connected to the body 6 by studs and nuts 8, and serves to close the open front of the body.

Sand supply pipe 9 is threaded into the upper

portion of the body 6 and delivers sand flowing from the sand box (not shown) to the interior of the trap body 6. The sand flows beneath a depending barrier 11 which serves to limit the height to which sand will rise in the body 6 by gravity flow. The cover 7 is formed with a passage 12 through which stirring air is drawn into the trap from the atmosphere. The entrance flow of air is caused by the ejector action which draws sand and air from the trap.

Entering air flows from the passage 12 into a stirring tube 13 which is pressed into a port on the inner face of the cover 7. The tube 13 has at its top a narrow longitudinal slot 14. The air thus flows partly through the slot 14 and agitates the sand so that the sand is carried at a proper rate to the Venturi throat.

To limit the stirring action to the proper intensity by-pass port 15 leads from the passage 12 to the space within the trap above the level of the sand. Increase in the size of the port 15 diminishes the effectiveness of the stirring action.

The body 6 is formed with two similar tubular extensions 16 and 17. These are aligned with one another as best shown in Figure 3 and receive the nozzle assembly which may be inserted from either end.

This assembly is housed in and sustained by a tube 18 which is encircled by aligning ribs dimensioned to fit the bore of members 16, 17. The tube 18 has a positioning flange 19 arranged to engage the end of extension 16 or 17 as the case may be. Near the flange the tube 18 is provided with a positioning pin 21 which engages one of the notches 22 or 23 formed in the extensions 16 and 17 respectively. The purpose of the positioning pin 21 is to assure that a lateral port 24 formed in the tube 18 is presented downwardly. This port 24 then communicates with the chamber within the body 6.

Threaded into the entrance end of the tube 18 is a nozzle tube 25 into the outer end of which the air supply pipe 26 is threaded after the sand trap has been mounted on the locomotive. A nozzle tip generally indicated by the numeral 27 is threaded into the inner end of the nozzle tube 25. This has a jet nozzle port 28 surrounded by a rim 29. At its rear it has a tubular extension 31 which is cross-drilled as indicated at 32 to serve as a strainer. The cross-drilled ports 32 are smaller than the jet nozzle passage 28 and so protect it against clogging. A removable plug 33 closes the rear end of the tip unit and may be removed on occasion.

Mounted in an annular seat formed in the dis-

charge end of tube 18 is a Venturi throat 34 preferably formed of rubberlike material and shaped to project beyond the annular nut 35 which clamps it in its seat.

There is a union fitting 36 which seats against the end of extension 17 (when the parts are assembled as shown in Figure 3) and is held by a union nut 37. The fitting 36 also seats against the end of the Venturi throat 34, which thus functions as a gasket to produce a tight seal. A union nut 38 identical with nut 37 is shown threaded on the end of extension 16. Sand discharge pipe 39 is connected to the fitting 36 and leads to the rail.

It will be apparent that the tube 18 positions the nozzle and the Venturi throat and thus forms a complete self-sustaining unit. This unit may be inserted into the aligned bores of extensions 16 and 17 from the left as shown in Figure 3, or it may be inserted from the right. In the latter case the nuts 37 and 38 are interchanged, the nut 38 engaging the tube 18, and the nut 37 the union fitting 36. In this way the trap may be assembled as either a righthand or a lefthand trap prior to the connection of the pipes 26 and 39.

Removal of the cover plate 7 gives access to the trap chamber and withdraws the stirring nozzle 13. No claim is here made to this detail which is the invention of another. The disconnection of pipe 26 and release of nut 38 permits the removal of the tube 18 with all the ejector parts. After such removal these parts may be removed individually from the tube 18 and cleaned or replaced as occasion may demand. This makes it possible to associate any desired type of nozzle with any desired type of Venturi throat.

Since the nozzle tip 27 is interchangeable, the simple interchange of tips controls the coordination of the size of the strainer ports 32 with the jet nozzle port 28. The height of rim 29 can be chosen to control the sand entrance passage to the Venturi throat.

While one embodiment of the invention has

been described in considerable detail this represents merely the best known embodiment of the invention and is intended to be illustrative and not limiting.

What is claimed is:

1. In a sand trap, the combination of a body having a sand-inlet connection, a sand-retaining chamber to which said connection leads and an open-ended transverse passage intersecting said chamber; an ejector assembly insertable into said passage in relatively reverse positions from respective ends thereof, said assembly comprising a jet nozzle with air supply connections, and a Venturi throat of rubber-like material and a sustaining sleeve serving to position said nozzle and throat in fixed coactive relation and so that the end of the throat is exposed at the end of the sleeve; a sand-discharge connection; and means operable interchangeably to connect the air supply end of the assembly to the body, and to connect the sand discharge connection to the body and seal it against the exposed end of the Venturi throat.

15 2. In a sand trap, the combination of a body having a sand-inlet connection, a sand-retaining chamber to which said connection leads and an open-ended transverse passage intersecting said chamber; an ejector assembly insertable into said passage in relatively reverse positions from respective ends thereof, said assembly comprising a tube having positioning means to engage the body and position the tube when the tube is inserted in either direction into said passage and a lateral port then so located as to communicate with said

30 3. In a sand trap, the combination of a body having a sand-inlet connection, a sand-retaining chamber; an ejector assembly insertable into said passage in relatively reverse positions from respective ends thereof, said assembly comprising a tube having positioning means to engage the body and position the tube when the tube is inserted in either direction into said passage and a lateral port then so located as to communicate with said chamber, a combined jet nozzle and strainer removably mounted in one end of said tube and terminating adjacent said port, and a Venturi throat removably mounted in the other end of said tube beyond said port; a sand discharge connection; and two threaded connectors, one associated with each end of said passage, and either adapted to fix said tube in the body while the other connects the sand discharge connection with the Venturi throat.
